CLAIM

The ornamental design for a fan cart, as shown and described.

DESCRIPTION

FIG. 1 is a top, front right perspective view of a fan cart showing our new design;

FIG. 2 is a top, front left perspective view thereof;

FIG. 3 is a bottom, front, right perspective view thereof;

FIG. 4 is a bottom, front, left perspective view thereof;

FIG. 5 is a rear, left, perspective view thereof;

FIG. 6 is a front elevational view thereof;

FIG. 7 is a rear elevational view thereof;

FIG. 8 is a right side elevational view thereof;

FIG. 9 is a left side elevational view thereof;

FIG. 10 is an enlarged top plan view thereof;

FIG. 11 is an enlarged bottom plan view thereof; and,

FIG. 12 is another top, front, right view thereof.

The broken lines in the figures are for the purpose of illustrating portions of the fan cart that form no part of the claimed design.

The cord of the fan cart is shown with a symbolic break in its length. The appearance of any portion between the break lines, including the break wavy lines form no part of the claimed design.
